The ornamental design for a holder for sugar and sugar substitute packets, as shown and described.

DESCRIPTION

FIG. 1 is a top, front, left side perspective view of a holder for sugar and sugar substitute packets showing my new design;

FIG. 2 is a left side elevation view thereof, the opposite side being identical;

FIG. 3 is a top plan view thereof;

FIG. 4 is a rear elevation view thereof; and,

FIG. 5 is a front elevation view thereof.

The undisclosed bottom view is planar and unornamented.
